Attorneys.

UNITED STATES PATENT OFFICE.

FRANK REGERO, OF MACON, GEORGIA.

FOUNTAIN-PEN.

1,398,800.

Specification of Letters Patent. Patented Nov. 29, 1921.

Application filed June 30, 1921. Serial No. 481,444.

To all whom it may concern:

Be it known that I, FRANK REGERO, a citizen of the United States, residing at Macon, in the county of Bibb and State of Georgia, have invented or discovered certain new and useful Improvements in Fountain-Pens, of which the following is a specification, reference being had therein to the accompanying drawings.

10 This invention relates to so-called self-filling fountain pens, and has for its object to provide a fountain pen of this class which is simple in construction and convenient in operation.

15 In the accompanying drawing Figure 1 is a sectional view of the improved fountain pen with the parts in closed position. Fig. 2 is a similar view of the filling piston drawn out to the position which it will occupy 20 when the chamber of the pen has just been filled. Fig. 3 is a detail view of the fixed sleeve within the casing.

25 Referring to the drawing, 12 denotes the hollow casing and 13 the pen holding part which may be mounted in the forward end of the casing in the usual manner, said forward end being preferably provided with a threaded portion 14 on which a cap 14^a may be screwed. The part 13 is provided with a 30 tubular extension or sleeve 15 having openings 16; and 17 is a second sleeve or valve having a close sliding fit within the said sleeve 15, said valve sleeve 17 having openings 18. The valve sleeve 17 is provided 35 with a tubular extension 19 preferably having an enlarged or flanged end portion 20, said tubular extension 19 having also an enlarged part or annular rib 20^a.

40 Mounted within the casing 12 is a piston sleeve 21 having at its inner end a loose sliding fit within the said casing 12. The piston sleeve 21 is preferably closed at its outer end by a cap 20^b, and thus by drawing it out it will create a suction within the chamber of 45 the casing 12, so that when the pen is dipped into an ink receptacle and the said sleeve 21 is drawn out ink will be drawn through a passageway 23 into the chamber of the casing 12, to fill the same.

50 When the parts are in the closed position shown in Fig. 1 the openings 16 in the sleeve 15, and the openings 18 in the sleeve 17 will be in register with each other, thus providing an open valve through which, in filling, 55 the ink may enter the chamber of the casing 12. When, however, the piston sleeve 21 has

nearly reached its full outer position the flange or enlargement 21^a at the inner end thereof will come in contact with the enlarged part 20^a on the tubular extension 19 of the sleeve 17 and thus draw the said sleeve 17 slightly outward so as to bring the openings 16 and 18 out of register with each other, as shown in Fig. 2, and thus close the valve afforded by the said openings in the sleeve parts 15 and 17.

50 Screwed into the outer end of the casing 12 is a ring or gland 23 which is screwed in place after the piston sleeve has been inserted in the casing 12, said ring or gland, 70 or the interposed cork packing ring 24, if the latter be employed, serving as a stop to prevent the piston sleeve from being drawn entirely out of the casing 12. The cork packing ring 24, fitting tightly between the 75 casing 12 and the piston sleeve 21, assures a proper suction action of the latter as it is drawn out in filling the pen. After the chamber of the pen casing 12 has been filled with ink, by drawing the piston sleeve 21 outward, and said sleeve is to be returned to its original closed position shown in Fig. 1, the air in the chamber of the said piston sleeve will pass inward through the tubular extension 19 of the sleeve 17 and also 80 through the sleeves 15 and 17 and the passageway 22; and when the said piston sleeve has nearly reached its closed position the cap 20^b will come in contact with the flange or enlarged portion 20 on the tubular 85 extension 19 of the sleeve 17, thus forcing said sleeve inward, and thereby again bringing the openings 18 in the said sleeve 17 into register with the openings 16 of the sleeve 15, so that the valve afforded by these 90 openings and the parts 15 and 17 will then be opened, thereby enabling the ink in the chamber of the pen casing 12 to flow through the passageway 22 to the pen.

95 From the foregoing it will be understood 100 that the invention provides a self-filling fountain pen of simple construction, and which will be convenient and efficient in operation.

Having thus described my invention I 105 claim and desire to secure by Letters Patent:

1. In a fountain pen, the combination with an outer casing affording an ink chamber of a valve comprising two sleeves provided with openings, one of said sleeves being movable relative to the other to cause 110 said openings to register with each other

when desired, a piston sleeve slidably mounted within said casing, and means whereby said valve will be closed when said piston sleeve is drawn outward, and will be opened when said piston sleeve is moved inward.

2. In a fountain pen, the combination with an outer casing affording an ink chamber, of a sleeve fixed within said casing and provided with openings, a movable valve sleeve having a close sliding fit within said fixed sleeve and also provided with openings which may be caused to register with the openings in said fixed sleeve, said valve sleeve having a tubular extension provided with an enlarged portion, a piston sleeve fitted to slide within said casing and having a closed outer end, said piston sleeve having means adapted to engage the said enlarged portion of said tubular extension to move the said valve sleeve outward when the said piston sleeve is moved outward, said piston sleeve having a part adapted to engage said tubular exten-

sion to move said valve sleeve inward when said piston sleeve is moved inward.

3. In a fountain pen, the combination with an outer casing affording an ink chamber, of a pen-holding member fitted to said casing and carrying an inwardly extending sleeve provided with openings, a second and movable sleeve having a close sliding fit within said first-named sleeve and also provided with openings which may be caused to register with the openings in said first-named device, said second sleeve having a tubular extension, a piston sleeve fitting within said outer casing, said piston sleeve and tubular extension having parts arranged for engagement with each other so that when said piston sleeve is nearly or fully drawn out, to fill the pen, the valve, afforded by said sleeves with openings, will be closed, but which valve will be opened when said piston sleeve is moved inward.

In testimony whereof I affix my signature. 45
FRANK REGERO.
